UNITED STATES PATENT OFFICE.

WILLIAM C. HUGULEY, OF NEWARK, NEW JERSEY, ASSIGNOR TO THE SPECIALTY PRODUCTS COMPANY, OF NEWARK, NEW JERSEY, A CORPORATION OF NEW JERSEY.

BABBITTING APPARATUS.

1,331,769.

Specification of Letters Patent. Patented Feb. 24, 1920.

Application filed July 11, 1919. Serial No. 310,110.

To all whom it may concern:

Be it known that I, WILLIAM C. HUGULEY, a citizen of the United States, residing in the city of Newark, county of Essex, and 5 State of New Jersey, have invented certain new and useful Improvements in Babbitting Apparatus, of which the following is a full, clear, and exact description, such as will enable others skilled in the art to which 10 it pertains to make, construct, and use the same, reference being had to the accompanying drawings, and to numerals of reference marked thereon, forming a part of this specification.

15 My invention relates to machines for casting small articles of various kinds and classes of metal, as for instance, for applying Babbitt metal to engine connecting rods; and the object thereof is to provide an improved machine of this class which is simple in construction and efficient in operation, and which may be conveniently manipulated.

The primary object of my invention is to 25 take the usual connecting rod having a wrist pin bearing at one end thereof and a crank pin bearing box at the other end, said crank pin bearing box usually comprising two halves the former of which is integral with 30 the rod, and the latter of which is separate and may be attached to the former by bolts extending through both and retained in place by nuts, and to cast a Babbitt bearing in the crank pin bearing box which will not 35 be spongy or porous, but possessed of the requisite density.

With these and other objects in view the invention consists in novel details of construction and combination of parts more 40 fully hereinafter disclosed and particularly pointed out in the claims, it being understood that changes in the precise embodiment of the invention herein disclosed can be made within the scope of what is claimed, 45 without departing from the spirit of invention.

The invention has been illustrated in its preferred embodiment in the accompanying drawings; wherein:

50 Figure 1 represents, a longitudinal section of the upper and lower divided dies with the core in position and showing in dotted lines a connecting rod clamped in operative position between the said upper and lower 55 divided dies.

Fig. 2 represents, a view of the upper die looking at it in the direction indicated by the arrow shown at the left in Fig. 1.

Fig. 3 represents, a view of the lower die looking at it in the direction indicated by the arrow shown at the right in Fig. 1.

Fig. 4 represents, a transverse section taken on line $\alpha-\alpha$ in Fig. 2.

Fig. 5 represents, a transverse section taken on line $\alpha-\alpha$ of Fig. 3.

Figs. 6 and 7 represent, respectively, end and side elevations of the completed babbitted bearing removed from the connecting rod.

Fig. 8 represents, a side elevation of the 70 babbitted bearing as it leaves the divided dies, and shown removed from the connecting rod.

Fig. 9 represents, an end view of said bearing looking in the direction indicated by the arrow in Fig. 8.

Fig. 10 represents, a transverse section taken on line $\alpha-\alpha$ of Fig. 8; and looking in the direction of the arrow; and

Figs. 11 and 12 represent, respectively, 80 a side elevation and an end view of the core used in connection with the divided dies.

Similar characters of reference are shown in all of the above described views, to indicate corresponding parts.

In the drawings 1 represents the upper divided die; 2 represents the lower divided die; and 3 represents the core which is movably secured to the platen 4 to which the upper die 1 is secured, and which engages with 90 both the upper and lower dies as clearly illustrated in Fig. 1 of the drawings.

The dies 1 and 2 are connected in the usual manner as is common in die casting machines so that the two dies and core can be 95 brought together in the position illustrated in Fig. 1 of the drawings with the recessed portion 6, in the underside of the platen 5, fitting over the outlet of the cylinder containing the molten metal, not shown.

100 The molten metal, as is common, passes from the outlet of the cylinder containing the same into the diametrically oppositely arranged passages 7 and 8 which are arranged one in each section 18 of the divided die 2 and from there is forced upward through said die around the core 3 into the crank pin bearing box of the connecting rod 9 illustrated in dotted lines in Fig. 1 of the drawings, and thence upwardly into the die 110

1 and around the upper stepped portion of the core 3 where it is chilled and sealed.

The construction of the upper and lower sectional or divided dies 1 and 2 together with the core 3 is such, that they possess important advantages over similar dies used in die casting machines, in that the path of the metal is of such a construction that there is absolutely no chance for the formation 10 of blow holes in the babbitt bearing and the result is that a babbitt bearing is produced possessing the highest degree of density and one that will not be spongy or porous.

- 15 The upper divided die 1 consists of the two sections 10-10 fitted into suitable gibs 11-11 secured to the under side of the platen 4, and is provided with the cylindrical aperture 12 and a series of stepped portions 13-13-13 designed to receive the cylindrical portion 14 and the stepped portions 15-15-15 of the core 3.
- 20 The apertured portion 12 of the die 1 is further provided with preferably four pads 16 which contact with the part 14 of the core 3 and which form the vents 17 of the babbitt bearing illustrated in Fig. 8 of the drawings.

- 25 The lower divided die 2 consists of two sections 18-18 fitted into suitable gibs 20 secured to the upper side of the platen 5, the central portions of the sections 18-18 are recessed to receive the core 19, which is secured to the platen 5 in any desired or 30 convenient manner.

In each section 18 of the lower die 2 passage ways 7 and 8 are formed to permit the molten metal to be forced, from the cylinder containing the same, into the said passage ways and up around the cylindrical portion 21 of the core 3.

- 40 The end of the core 3 adjacent to the cylindrical portion 21 is provided with a projection 22 designed to be received into the aperture 23 of the core 19, in order to properly position the core 3 with relation to the dies 1 and 2.

It will thus be seen that if the compression lever of the machine (which is not 45 here shown) is given the usual quick hard pull the molten metal from the cylinder containing the metal will be forced into the lower die through the passages 7 and 8, then into the crank pin bearing of the connecting 50 rod 9 around the portion 21 of the core 3 and up into the upper die around the cylindrical portion 14 of the core 3 where the metal is restricted and deflected in its path by coming into contact with the stepped 55 portions 15 of the core and the stepped portions 13 of the die 1.

Before the metal reaches the largest stepped portion of the core and die it usually becomes chilled and forms a seal.

- 60 65 The section 10-10 adjacent the upper-

most stepped portion 13 are cut away as illustrated at 24 to provide a passage way for the escape of the air which is in the space surrounding the core 3.

From an inspection of Figs. 6 and 7 of 70 the drawings, which shows the completed babbitt bearing removed from the connecting rod bearing, and an inspection of Fig. 8 of the drawings which illustrates the babbitt bearing as it leaves the upper and 75 lower dies, the same is shown provided in Fig. 8 at one end with runners 25, and at its upper end with the cylindrical wall 26, from which project the cylindrical stepped portions or risers 27-27 and 27.

80 It will be noted that the wall of the cylindrical portion 26 is thinner than the wall of the bearing, and that the walls of the stepped portions 27 are all of the same thickness as the wall 26, the idea being that 85 these stepped portions in the core and die form a restricted or stepped passage way for the molten metal.

The porous or spongy part of the metal 90 is always found in the cylindrical wall 26 and the stepped portions 27 which, of course, is to be understood are to be removed as well as the runners 25, in order to form the completed bearing as illustrated in Figs. 6 and 7 of the drawings.

95 It will thus be seen that by the employment of the two dies and the core, the upper die being provided with a plurality of stepped portions corresponding with a similar plurality of stepped portions formed on 100 the core, I am enabled to provide a stepped passage way for the metal which as it enters the passage ways in the lower die is forced around the core, thereby expelling the air from around the core and filling up the air 105 space between the core and the recess in the upper die and from there by means of the stepped portions on the core and in the die the metal is caused to be deflected from one stepped portion onto the other, until it 110 reaches the uppermost stepped portion where it is chilled and forms a tight seal.

115 Experience has demonstrated that the organization above described is a highly efficient one, and while I have shown the preferred embodiment of my present invention, I do not wish to be limited to the exact details of construction shown and described, as obvious modifications thereof, not involving the exercise of invention, may be 120 made by any skilled mechanic, and such departures from what is herein set forth, I consider within the scope and terms of my claims.

I claim.

125 1. A babbittting apparatus comprising upper and lower sectional dies, a core engaging with said dies, the lower die being provided with passage ways for the molten metal and the upper die being provided 130

with stepped portions corresponding with stepped portions formed on the core to form a stepped passage way for the metal in the upper die.

- 5 2. A babbittting apparatus comprising upper and lower sectional dies, a movable core engaging with said dies, the upper end of which is provided with stepped portions, the lower die being provided with 10 passage ways for the molten metal, and the upper die being provided with stepped portions corresponding with the stepped portions formed on the core to form a stepped passage way for the metal in the upper die.
- 15 3. A babbittting apparatus comprising upper and lower sectional dies, a movable core engaging with said dies, the upper end

of which is provided with stepped portions, the lower die being provided with passage ways for the molten metal, and the upper die being provided with pads to engage with said core forming vents and further provided with stepped portions, and the upper die being provided with stepped portions corresponding with the stepped portions formed on the core to form a stepped passage way for the metal in the upper die. 20 25

This specification signed and witnessed this 2nd day of July 1919.

WILLIAM C. HUGULEY.
